JOHN D. SHELY AND JOHN H. SHELY, OF LEXINGTON, KENTUCKY, ASSIGNEES TO THEMSELVES AND RICHARD C. MORGAN, WILLIAM A. SHELY, AND ALDA M. SHELY, ALL OF SAME PLACE.

HEMP BRAKE AND CLEANER.

SPECIFICATION forming part of Letters Patent No. 451,438, dated April 28, 1891.

Application filed March 14, 1890. Serial No. 343,916. (No model.)

To all whom it may concern:

Be it known that we, JOHN D. SHELY and JOHN H. SHELY, citizens of the United States, and residents of Lexington, in the county of Fayette and State of Kentucky, have invented certain new and useful Improvements in Hemp Brakes and Cleaners, of which the following is a specification.

Our invention relates to hemp brakes and cleaners. The drawings show a form of brake and cleaner properly adapted to the cleaning of hemp, but it is equally adapted to the cleaning of flax or any other lints, such as jute, flax, &c.

15 The objects of our invention are, first, to improve the machinery for breaking the hemp, and, second, to deliver the same to a cleaner, which removes the hurds, all of which will be fully set forth in the description of the accompanying drawings, making a part of this specification, in which—

Figure 1 is a side elevation of our improvement. Fig. 2 is a sectional elevation on line *xx*, Fig. 1. Fig. 3 is a sectional elevation on line *yy*, Fig. 2. Fig. 4 is a sectional elevation showing the detail of the feed-roll adjustment. Fig. 5 is a perspective view of the bottom cleaner-frame, and Fig. 6 is a perspective view of the top cleaner-frame inverted. Fig. 7 is a sectional elevation on line *zz*, Fig. 1. Fig. 8 is a side view of a portion of the conveyer for carrying off the hurds that are thrown through and above the upper cleaner-frame.

35 A represents the sills of the machine; B the rear post, and C the front post, of the main frame.

D represents longitudinal top plates of the frame, and E the cross-girders.

40 G represents a secondary sill bolted onto the top sill A simply for the purpose of elevating the pulleys.

1 represents the main driving-shaft. It is provided with fast and loose pulleys F I, by 45 which power is received.

2 2 represent crank-wheels, which are provided with crank-pins 62.

3 3 represent pitmen conveying motion to the vibratory breaker-frame 4. This frame

is mounted to slide between guides 6 7, attached to rearwardly-inclined posts 5 and C. 50 8 9 represent stationary guides gained into posts C.

10 11 represent guides on the rear side of said sash-frame, gained into posts 5. 55

12 13 represent feed-rolls. The lower one is preferably mounted on stationary journals secured to posts C. The upper one is journaled in a sliding journal-box 14, which moves in gains in posts C. 60

15 represents an upwardly-projecting lug or saddle attached to the top of said journal-box. The upper feed-roller which journals therein is held to its work preferably by weight-levers 16, pivoted on centers 17. The 65 saddle 15 is rounded upon its top face, so that as it is raised the fulcrum-point is brought nearer to the center 17, thereby increasing the weight as the weighted levers are raised. The weights 18 are likewise shown 70 as adjustable upon the levers 16, so that more or less power may be employed for holding the feed-roller to its work. The weights 18 may be held in any desired position on the levers 16 by means of binding-screws 63; or 75 they may be adjustably held on said levers by any suitable means.

19 represents a series of dividers attached to the cross-bar 20, which is rigidly secured to the posts 5 in rear of the feed-guides 10 80 and 11.

21 represents a stationary cleaner-frame. It is composed of parallel longitudinal slats 22 and frame-pieces 23, by means of which it is loosely supported on the braces D, which 85 are secured at each end to the posts B and C.

In the projecting ends of the frame-pieces 23 are perforations 64 for the passage of guide-bolts 65, around which are placed springs 66, that permit a slight yielding upward movement of the cleaner-frame 21 to relieve it from strain under pressure of the hemp passing beneath said frame. Aside from this slight yielding movement of the cleaner-frame 21, it is practically stationary. The guide-bolts 65 90 are passed through the frame-pieces 23 and braces D, as shown in Fig. 1. Each bolt is provided on its lower end with a nut 67, and 95

has about midway its length a rigid collar 68, that is countersunk in the upper side of the brace and together with the nut 67 holds the bolt in place.

5 Between the collar 68 and end cross-piece 23 of the cleaner-frame is a nut 69, by which a slight vertical adjustment may be given to said cleaner-frame, and on the upper end of the bolt is a nut 70, by which the spring 66 10 can be compressed to any desired degree to vary its pressure on the end cross-piece of the cleaner-frame, which is thus made both adjustable and yielding.

24 represents a vibratory cleaner-frame. 15 It is composed of parallel longitudinal slats 25, which are rigidly secured to the longitudinal rails 26 by means of cross-rails 27 and clips 67, passed over the ends of the slats 25 and engaged with the end cross-rails 27, as 20 shown in Fig. 5. This frame is made vibratory by the following instrumentalities:

11 represents a sprocket-wheel upon shaft 1, which transmits motion to the sprocket-wheel 1 on the shaft 28, which is journaled 25 upon brackets 29.

30 30 represent crank-wheels keyed to each end of said shaft.

34 34 represent crank-pins. These crank-pins are preferably made adjustable by being 35 stepped in the slide-blocks 35, which are journaled in the recess 36, pierced in the face of said crank-wheels 30.

40 40 represent brackets attached to the longitudinal frame-pieces 26. The rear end 35 of said vibratory cleaner-frame 24 is preferably supported upon friction-rollers 41, which are journaled between the brackets 42 and the frame-piece 26, as shown in Fig. 5.

43 43 represent ways formed in the pillow-blocks 44. 45 45 represent guides secured to said pillow-blocks for holding down the journals on the rear end of said frame.

The mode of operation is as follows: The 15 hemp, flax, or other stalks to be treated are fed in between the feed-rollers 12 and 13, the guides 8 and 9 holding them in proper position to be acted upon by the vibratory or breaking frame 4. K represents an opening in said breaker-frame through which the 20 stalks are passed. This frame is rapidly vibrated by means of its crank-wheels and pitmen, and strikes the stalks and carries them rapidly back and forth between the stationary guides, breaking the pith in both directions. We prefer to have the stroke of the 25 pitmen 3 adjustable by attaching their crank-pins in the same manner as the adjustable crank-pins 34. (Shown in Fig. 1.) As the hemp is passed forward by the feed-rollers 30 and treated by the breakers it is carried in between the cleaner-frames 21 and 24. By referring to Fig. 3 it will be observed that the 35 posts C and 5 are inclined slightly backward, so as to cause the breaker-frame 4 to move 40 in an oblique plane between the stationary guides 8, 9, 10, and 11, that are attached to

1 said posts. The rear guides 10 and 11 are located slightly below the corresponding forward guides 8 and 9, so that the hemp stalks when acted on by the breaker-frame will 70 readily fall away from said guides and pass at once to the cleaner-frames without clogging the guides or breaker-frame. By arranging the breaker-frame and its guides in this manner the hemp is broken alternately against 75 the upper guides and the lower forward guide 9, but not on the lower rear guide 11, which is located below the limit of stroke given to the breaker-frame 4, (which is represented in Fig. 3 as being at the lower limit of its stroke,) 80 and so provides a free clearance for the broken stalks on their way to the cleaner-frames. The opening K in the breaker-frame and the several guides against which the stalks are broken have square edges that are adapted 85 to break the stalks without injury to the lint, and as the stalks are made to pass at once to the cleaner-frames after being broken the 90 lint is not torn or crushed and no tow is produced. The obliquely-reciprocating breaker-frame supported in a rearwardly-inclined position, together with the above-described arrangement of front and rear guides with relation to said breaker-frame, is one of the 95 chief distinguishing features of our invention 95 whereby we are enabled to produce the best results in the separation of hurds by said breaking devices and in facilitating the free passage of the broken stalks to the cleaners, so that the breaker will not become clogged 100 and crush or injure the fiber. These results are not attained so well or with equal facility in machines in which the breaker reciprocates vertically between guides that are substantially in the same plane. The 105 arrangement of longitudinal slats in the cleaner-frames by which the hemp is caused to pass through the machine lengthwise and parallel with said slats also obviates any liability 110 to producing tow, as commonly experienced 110 in hemp-brakes of ordinary construction. The frame 24 is made preferably to vibrate in the path indicated by the dotted lines and arrows a b. (See Fig. 1.) Motion is imparted to the vibratory frame by means of 115 the crank-wheels 30. As the cleaner-slats 25 are raised they come in contact with the hemp and force it up into the dividers 19, which make openings in the gavel or stream 120 of fiber being fed under them. The vibratory 120 frame moves forward, so as to take up the hemp as it is fed by the feed-rollers. The cleaner-slats or singers 25 of the vibratory frame pass between the cleaner-slats 22 of 125 the stationary frame, forcing the hurd out of the hemp, but particularly opening or making divisions in the charge, so that the hurds are separated out from the lint, a part of them being thrown out up through the upper cleaner-frame and a part of the hurds dropping down through the vibratory frame. By 130 referring to Fig. 1 it will be observed that

the stationary and vibratory cleaner-frames are separated from each other a sufficient distance throughout their entire length to enable the hemp or other material acted on to pass 5 all the way between them, the gavel being fed in at one end of said frames and discharged at the other, and in thus passing through the cleaners lengthwise and parallel with the cleaner-slats the gavel or stream of 10 fiber is divided longitudinally and thoroughly cleaned by the action of the parallel and longitudinal slats, which also separate the hurds from the lint.

In order to carry off the hurds which are 15 thrown out through the stationary frame 21, we have provided a conveyer M, which is suitably journaled to the posts B at the lower rear end of the stationary frame. This conveyer is preferably an ordinary worm, which 20 receives its motion from the pulley N (see Fig. 2) by a belt N', Fig. 1. Any form of conveying mechanism, however, may be employed to carry off the surplus hurds. As the hurds are thrown out with great force by 25 the rapid movement of the vibratory cleaner-frame we provide an elevated shield O, secured to the posts B at the rear end of the machine, so as to prevent the hurds from being thrown over onto the apron P of the 30 cleaner-frame, where the clean hemp is removed by the operator. By referring to Fig. 1 it will be seen that the lower end of the shield O is extended forward over a portion of the cleaning devices to afford a floor for 35 the conveyer and to prevent any hurds from falling back into the lint that is passing through the cleaner. This apron is preferably canvas and stretched across from the side rails 26 of the vibratory frame 24 in rear 40 of the fingers 25; but any material may be used for this purpose. We prefer to have the vibratory frame 24 move forward in its upward and downward motion in the act of receiving and cleaning the broken stalks, as 45 indicated in dotted lines a b, as this takes up the hemp and assists in pulling it through and prevents its knotting or tangling up in its delivery from the breakers to the cleaners.

We believe we are the first to employ cleaners in which one is stationary and the other is vibratory, where the cleaner slats or strips run longitudinally with the fiber. A very important advantage is obtained by this means: First, it makes openings or divisions 50 in the charge being acted upon to allow the hurds to pass out; second, it avoids making tow or cutting the fibers, which will always occur whenever the cleaner slats, strips, or fingers are passed transversely across the lint 55 or fibers.

Another advantage is obtained in case short stalks accidentally pass through the breakers without being broken. These stalks will then run across the longitudinal slats or 60 fingers of the cleaner-frames and be operated on by them and both broken and cleaned, so

that the result is the hemp passed through these cleaners is not only cleaned much freer from hurds, but the accidental passing through the cleaner-frames of unbroken and 65 uncleaned stalks is avoided.

We have also found that in practice we can clean hemp which has been overrotted, so that it cannot be well cleaned by hand without breaking into tow. By means of our 70 double-stroke reciprocating slide 4, working between the two sets of guides, another advantage is obtained. A large part of the hurds is cleaned out by the rapid strokes of the reciprocating frame 4, thereby saving a 75 large amount of work by the cleaners.

While we have shown one end of the vibratory frame as supported upon longitudinal moving journals, yet we do not wish to confine ourselves to this means of vibrating 80 the rear end of the frame, as the lower end of the frame 25 might be loosely suspended by means of rods 50 (shown in dotted lines in Fig. 1) with very nearly as good results.

We have shown the dividers 19 as stationary instead of revolving, as we deem this the best mode, as it is less liable to tangle the fiber than if they are made to travel.

In order to convey motion to the feed-rolls, we have provided the spur-gears c d and pinion-wheels e, as shown in Fig. 1. f represents the sprocket-wheel on the shaft 45, and 46 represents a sprocket-wheel keyed to the shaft of the lower feed-roller 13, thereby carrying the sprocket-roll 46 outside of the sweep 90 of the crank-wheels and the crank-pins 2 and transmitting motion to the feed-rollers outside of the frame. 47 represent braces, one of which is attached to each post C and sill A, so as to strengthen the frame and prevent 95 vibrations. 68 is a sprocket-chain that connects the sprocket-wheels f and 46 for driving the feed-rollers.

Having described our invention, what we claim is—

1. In a hemp-brake, the combination, with a reciprocatory breaker-frame, of front stationary guides and rear stationary guides located on different horizontal planes adjacent to the opposite sides of said breaker-frame 115 to afford a clearance for the stalks, substantially as described.

2. In a hemp-brake, the combination, with a reciprocatory breaker-frame, of guides adjacent to the front and rear sides of said breaker-frame for holding the stalks to the stroke of said frame, the rear upper guide being located below the horizontal plane of the front upper guide to afford a clearance for the stalks, substantially as described. 125

3. In a hemp-brake, the combination, with a reciprocatory breaker-frame, of guides adjacent to the front and rear sides of said breaker-frame for holding the stalks to the stroke of said frame, the lower rear guide being located below the horizontal plane of the lower front guide, substantially as described. 130

4. In a hemp-cleaning machine, a frame provided with longitudinal slats, in combination with driving mechanism for effecting a vibratory movement of said frame in an elliptical path in a plane parallel with the slats, substantially as described.
5. The combination of a reciprocating breaker-frame having a passage for stalks, stationary guides in front and rear of the breaker-frame for holding the stalks to the action of said frame, and a cleaner having a vibratory frame provided with slats arranged longitudinally in the direction of the path of the fiber or stalks for removing hurds from the lint, substantially as described.
6. In a hemp-brake, the combination of feed-rollers, a breaker device, and a cleaner having a vibratory frame for removing hurds from the lint and dividing the gavel longitudinally as it passes lengthwise of said cleaner, substantially as described.
7. In a hemp-brake, the combination, with a cleaner, of a reciprocating breaker and stationary guides in front and rear of said breaker for holding the stalks to the action of the breaker, said front and rear guides being located in different horizontal planes, substantially as and for the purpose described.
8. In a hemp-cleaning machine, the combination, with a cleaning mechanism, of a shield located above said cleaning mechanism to receive the hurds which are thrown out from the upper side of the lint, substantially as described.
9. A combined hemp brake and cleaner consisting of hemp breaking and cleaning devices and a series of dividers located between the hemp breaking and cleaning devices, substantially as described.
10. A combined hemp brake and cleaner consisting of a hemp-breaking device, a cleaner having a vibratory frame for removing hurds from the lint and dividing the gavel longitudinally as it passes lengthwise of said cleaner, and means for vibrating said frame in a plane intersecting and in line with the movement of the fiber, substantially as described.
11. In a hemp-brake, the combination, with the obliquely-reciprocating breaker-frame supported in an oblique rearwardly-inclined plane, of guides at the front and rear of said breaker frame for holding the stalks to the stroke of said frame, the lower rear guide being located below the plane of the front guides and below the limit of stroke given to the breaker-frame to afford a clearance for the broken stalks, substantially as described.
12. In a hemp-brake, the combination, with the obliquely-reciprocating rearwardly-inclined breaker-frame, the cleaners, and the feed-rollers, of the front stationary guides between said rollers and breaker-frame, and the rear stationary guides between the breaker-frame and cleaners and located below the plane of the corresponding front guides to afford a clearance for the broken stalks, substantially as described.
13. In a hemp-brake, the combination of the feed-rollers, the breaker-frame, the stationary and vibratory cleaner-frames, the front stationary guides between the feed-rollers and breaker-frame, and the rear stationary guides between the breaker-frame and cleaner-frames and located below the plane of the corresponding front guides, substantially as described.
14. In a hemp-cleaning machine, in combination with the feed rollers and breaking device, the series of stationary dividers 19, placed between the breaking and cleaning device, for dividing the hemp longitudinally in its passage to the cleaners, substantially as herein specified.
15. In a hemp-cleaning machine, cleaner-frames separated from each other throughout their entire length to afford a space for the gavel to be fed in at one end and discharged at the other, each of said frames comprising parallel longitudinal slats for removing the hurds from the lint and dividing the gavel longitudinally as it passes lengthwise between the frames and parallel with the cleaner-slats, substantially as described.
16. In a hemp-cleaning machine, the stationary frame 21, provided with longitudinal slats 22, in combination with the vibratory frame 24, provided with longitudinal slats 25, with driving mechanism for moving the vibratory frame in the path *a b*, substantially as herein specified.
17. A combined hemp brake and cleaner consisting, substantially, of the feed-rolls, the reciprocating breaker-frame 4, stationary guides on each side of the breaker-frame, and the stationary and vibratory cleaner-frames 105 provided with longitudinal cleaning-slats, substantially as described.
18. A combined hemp brake and cleaner consisting of the hemp-breaking device, the cleaner-frames, a series of dividers located between the hemp breaking and cleaning devices, and means for actuating one of the cleaner-frames, substantially as described.
19. In combination with the cleaner-frame 21, the conveyer M and the shield O, substantially as specified.
20. The combination, with an upper cleaner-frame and a lower cleaner-frame, each provided with longitudinal slats for removing hurds from lint, of a breaker-frame having a slot for the passage of stalks, and stationary guides in front and rear of the breaker-frame for holding the stalks to the action of said frame, the rear guides being located below the plane of the front guides to afford a clearance to the cleaner frames, substantially as described.
21. The combination of the longitudinally-slatted cleaner-frames, the rearwardly-inclined breaker-frame, the feed-rolls, the front

stationary guides, the rear stationary guides located below the plane of the front guides, and the stationary dividers located between the breaking and cleaning frames to divide 5 the hemp longitudinally in its passage to the cleaners, substantially as described.

22. The combination of the feed-rolls, the breaker-frame, the stationary guides in front and rear of said frame, the dividers in rear of 10 the breaker-frame, the stationary and vibra-

tory cleaner-frames, and the conveyer located above the stationary cleaner-frame, substantially as described.

In testimony whereof we have hereunto set our hands.
